(57) **CLAIM**

The ornamental design for a ceiling fan motor housing and light kit, as shown and described.

DESCRIPTION

FIG. 1 is a top perspective view of a first embodiment of a ceiling fan motor housing and light kit in the environment of a ceiling fan;

FIG. 2 is a bottom perspective view of the ceiling fan motor housing and light kit of FIG. 1;

FIG. 3 is a rear view of the ceiling fan motor housing and light kit of FIG. 1;

FIG. 4 is a front view of the ceiling fan motor housing and light kit of FIG. 1;

FIG. 5 is a right side view of the ceiling fan motor housing and light kit of FIG. 1;

FIG. 6 is a left side view of the ceiling fan motor housing and light kit of FIG. 1;

FIG. 7 is a top view of the ceiling fan motor housing and light kit of FIG. 1; and,

FIG. 8 is a bottom view of the ceiling fan motor housing and light kit of FIG. 1.

The broken lines showing a ceiling fan illustrate environmental subject matter only and form no part of the claimed design.

1 Claim, 8 Drawing Sheets
